UNITED STATES PATENT OFFICE.

PETER RASMUSSEN AND MANOEL F. GOULARTE, OF SELMA, CALIFORNIA.

SEWING-MACHINE.

1,228,966.

Specification of Letters Patent. Patented June 5, 1917.

Application filed July 5, 1916. Serial No. 107,627.

To all whom it may concern:

Be it known that we, PETER RASMUSSEN and MANOEL F. GOULARTE, citizens of the United States, residing at Selma, in the county of Fresno and State of California, have invented certain new and useful Improvements in Sewing-Machines, of which the following is a specification, reference being had to the accompanying drawings.

10 This invention relates to certain improvements in sewing machines and has relation more particularly to a device of this general character especially designed and adapted for use in connection with shoes and particularly in repairing the same; and it is an object of the invention to provide novel and improved means wherein the stitch forming mechanism, the needle operating means and the feed are under control of a single member.

20 The invention also has for an object to provide novel and improved means wherein the stitch forming mechanism includes a rotary shuttle and wherein said shuttle is maintained stationary during a predetermined period of movement of the needle relative to the shuttle.

A still further object of the invention is to provide a novel and improved device of 30 this general character including a reciprocating needle, a rotary shuttle and a feeding mechanism together with a rack mounted for reciprocatory movement and coacting with the shuttle, needle and feed to implement the requisite movement thereto upon a single stroke of the reciprocatory member, said reciprocatory member being preferably manually operated.

A still further object of the invention is 40 to provide a device of this general character with a novel and improved presser foot having coacting therewith means for automatically moving the same in a direction toward the work together with mechanical 45 means for moving said presser foot in a direction away from the work.

The invention also has for an object to provide a novel and improved feed comprising an arm mounted for rocking movement and for endwise movement whereby the same may be caused to properly engage the work to move the same in one direction relative to the needle, and wherein adjustable means is provided for coaction with 55 said member for varying the extent of feed

of the work in accordance with the requirements of practice.

The invention also contemplates for an object to provide novel and improved means whereby an effective tensioning means may 60 be employed in connection with the thread and whereby said means may be readily and conveniently adjusted to vary the tension.

Another object of our invention is to provide novel and improved means to wax the 65 thread to be wound upon the bobbin together with means whereby the wax may be maintained softened or melted when the thread is to be drawn therethrough.

Another object of the invention is to provide a novel and improved thread waxing device which includes a container supported by the machine and capable of adjustment relative thereto so that the container will not afford an obstruction to the work- 70 man or operator, and wherein the container is provided with effective means for removing the surplus wax from the thread after it has been passed through the container.

The invention also contemplates novel and 80 improved means whereby the thread, during the stitch forming operation, is substantially entirely protected against undue wear or frictional resistance whereby the defec- 85 tiveness of the operation is materially increased.

The invention consists in the details of construction and in the combination and arrangement of the several parts of our im- 90 proved sewing machine whereby certain im- portant advantages are attained and the de- 95 vice is rendered simpler, less expensive and otherwise more convenient and advantageous for use, all as will be hereinafter more fully set forth.

The novel features of the invention will hereinafter be definitely claimed.

In order that our invention may be the better understood, we will now proceed to describe the same with reference to the accompanying drawings, wherein—

Figure 1 is a view in side elevation of a sewing machine constructed in accordance with an embodiment of our invention, a portion of the device being shown in section;

Fig. 2 is a view in front elevation of the device as herein embodied with the lower part thereof broken away and with the operating pedal shown in section;

Fig. 3 is an enlarged view in front eleva- 110

tion of the head portion of the machine with parts in section;

Fig. 4 is a sectional view taken substantially on the line 4—4 of Fig. 3;

Fig. 5 is a sectional view taken substantially on the line 5—5 of Fig. 3;

Fig. 6 is a vertical sectional view taken through Fig. 3 at substantially the transverse center thereof with the burner attachment omitted;

Fig. 7 is a sectional view taken substantially on the line 7—7 of Fig. 3;

Fig. 8 is an enlarged view in rear elevation of the head of the device with the back plate omitted and certain of the parts in section;

Fig. 9 is a fragmentary view in elevation of the needle bar as herein included;

Fig. 10 is a transverse sectional view taken through the lower portion of the bar as disclosed in Fig. 9;

Fig. 11 is a fragmentary sectional view of the thread waxing box or cup as herein included;

Fig. 12 is a view in top plan of the tensioning device as herein embodied, detached; and

Fig. 13 is a sectional view taken substantially on the line 13—13 of Fig. 7 with certain of the parts omitted.

As disclosed in the accompanying drawings, 1 denotes a plate provided with the supporting legs 2 and with which is operatively engaged, as at 3, the upstanding tubular post 4 having its upper end provided with the outwardly directed annular flange 5. Suitably secured to the flange 5 are the supporting arms 6 for the table 7.

Mounted for reciprocatory movement within the post 4 and extending thereabove is the plunger 8, the lower extremity of which being reduced, as at 9. The reduced portion 9 is loosely directed through the plate 1 and has connected to its extended portion the head 10 which serves to limit the upward movement of the plunger 8 which, as herein disclosed, is automatically accomplished through the medium of the expandable member 11 herein disclosed as a conventional coil spring encircling the reduced portion 9 and interposed between the plate 1 and the lower end of the plunger 8 proper.

12 denotes a foot lever pivotally engaged at one end with one of the legs 2 and having an intermediate portion provided with a longitudinally disposed slot 14 through which extends the pin 15 carried by the head 10 and intersecting the kerf thereof. It will be self-evident that upon depressing the outer end of the lever 12, the plunger 8 will be caused to move downwardly for a purpose which will hereinafter be more fully referred to.

Extending upwardly from the table 7 is a head plate 16 having its rear face provided

with the guideway 17 disposed longitudinally thereof and in which is mounted for endwise movement the operating member 18 which extends through an opening 19 formed in the table 7 and is provided at its lower end with the longitudinally disposed extension 20 pivotally engaged, as at 21, with the upper end portion of the plunger 8.

The intermediate portion of the operating member 18 includes two separated bars 22 disposed longitudinally of the member 18 and arranged in parallelism, one of said bars being provided with the inwardly directed teeth 23 adapted to mesh with the pinion 24 affixed to the rearwardly directed stub shaft 25 of the shuttle carrier 26.

The shuttle carrier 26 comprises a disk-like member arranged for rotation within the cylindrical chamber 27 formed in the block 28 carried by the forward face of the plate 16, and said carrier 26 is positioned adjacent the inner end of said chamber 27. The shuttle carrier 26 is provided adjacent its periphery with the forwardly directed arm or lip 29 arcuate in cross section and which is adapted to be received within the recess 30 formed in the periphery of the shuttle S whereby it will be perceived that the shuttle S will be caused to rotate in unison with and in the same general direction as the carrier 26.

The shuttle S is adapted to have rotatably supported therein the bobbin B and the thread from the bobbin is directed through the opening 31 disposed through the wall of the shuttle. The shuttle S is also provided with the nose 32 adapted to engage the thread brought within the chamber 27 by the needle N whereby the requisite stitch is formed. It is also to be observed that the needle N passes over the forward face of the shuttle S.

In order to facilitate the insertion or removal of the shuttle S the outer end of the chamber 27 is normally open but is adapted to be closed by the plate 33 having its inner face provided with the inwardly directed flange 34 disposed on an annular line to assure the requisite clearance for the movement of the needle within the chamber 27 and which also contacts with the outer face of the shuttle S to cause the same to travel in a fixed path.

The plate 33 is provided adjacent its upper end with a laterally and outwardly directed wing 35 provided with a perforation 36 through which is directed the forwardly extending threaded shank 37 carried by the block 28. The inner portion of the perforation 36 is enlarged to accommodate the washer 38 threaded upon the shank 37 and provided with the notch 39 adapted to receive the pin 40 carried by the wing 35 and whereby said washer 38 serves in the nature of a jam-nut. The outer end portion of the

threaded shank 37 has engaged therewith the clamping nut 41 for a purpose which is believed to be self-evident.

The shank 37 has its inner end portion 5 smooth and loosely disposed within the recess or pocket 42 formed in the block 28 and has its inner end provided with a head 43. Interposed between the head 43 and the outer end of the pocket 42 is the expandable member 44 herein disclosed as a conventional coil spring encircled around the shank 37 whereby it will be perceived that the plate 33 is capable of slight yieldable movement relative to the block 28 in 10 order that the stitch operation may be materially facilitated.

The periphery of the plate 33 at the side opposite to the wing 35 is provided with a recess or pocket 45 which is adapted to 20 receive the spring-pressed locking member 46 slidably disposed through the adjacent portion of the block 28 or more particularly the face plate 47 secured thereto. The plate 47 is of such a length as to substantially entirely bridge the space between the lower portion of the block 28 and the upper face of the table 7. It is also to be noted that the upper portion of the block 28 is provided with an opening 48, the forward walls 25 30 whereof being flared in order to eliminate any obstruction to the movements of the threads during the stitch forming operation.

The forward portion of the block 28 is 35 provided with the upstanding portion 49 affording a straight horizontal surface serving as a work support, and said portion 49 is provided with the recess 50 for the passage of the needle N.

40 Coacting with the portion 49 is the presser foot 51 suitably secured to the lower ends of the parallel arms 52 depending from the slide 53 mounted for reciprocating movement within the guideway 54 formed in 45 the forward face of the plate 16 adjacent the upper end thereof, said presser foot 51 bridging the space between the lower ends of the arms 52 and provided therebetween with the opening 55 alining with the recess 50 and through which the needle N is also 50 adapted to pass. The slide 53 is provided with a laterally directed web or wing 56 from which extends an inwardly directed pin 57.

55 Secured to said pin 57 is an end portion of the retractile member 58, the opposite end portion of which being secured to the plate 16 at a predetermined point below said web or wing 56, said retractile member 60 58 being herein disclosed as a conventional coil spring and serving to automatically impart downward movement to the slide 53 in order to cause the presser foot 51 to properly engage the work.

65 The web or wing 56 has also operatively

engaged therewith a link 59 which is also pivotally engaged to the arm 60, said arm 60 being supported for rocking movement by the plate 16 and the connection 61 between the arms 60 and link 59 being eccentric to the connection 62 between the arm 60 and the plate 16, whereby it will be perceived that upward movement of the arm will result in the elevation of the slide 53.

63 denotes a pawl pivotally supported by the arm 64 extending laterally from the plate 16 and which engages the upper portion of the web or wing 56 to hold the slide 53 against undue upward movement when the same has been adjusted to bring the presser foot 51 in operative engagement with the work. As herein embodied, the upper portion of the pawl 63 has coacting therewith the expandable spring 65 for forcing the lower end of said pawl inwardly. It is also to be noted that the lower end of the pawl 63 is toothed, as at 66, to facilitate its coaction with the wing or web 56 and it is also to be noted that the lower end portion of said pawl 63 is provided with the shoulder 67 with which the upper end of the link 59 is adapted to contact in order to disengage the pawl 63 from said wing or web 56 upon the initial upward movement being imparted to the arm 60 to raise or elevate the slide 53.

The inner or rear face of the slide 53 is provided with the guideway 68 in which is arranged the needle bar 69, said needle bar 69 and slide 53 being arranged for relative independent reciprocal movement.

As is particularly illustrated in Figs. 9 and 10, the lower end portion of the needle bar 69 is provided with a slit 70 in communication with the bore thereof so that the needle N may be effectively held by the needle bar through the medium of the clamping screw 71.

The needle bar 69 at substantially midway its length is provided with the rearwardly directed pin 72 loosely disposed through the upper end portion of the operating member 18 whereby it will be perceived that upon reciprocation of the member 18 under the influence of the foot lever 12, the requisite movement will be imparted to the bar 69. It is also to be noted in Fig. 8 that the teeth 23 of the operating member 18 are interrupted adjacent the lower part thereof so that the shuttle carrier 26 will remain stationary during a portion of the movement of the operating member 18 and during a portion of the movement of the needle N, so that the needle N will have sufficient time to form the loop to be engaged with the under thread.

The pin 72 extends beyond the rear face of the operating member 18 and is loosely disposed through the elongated slot 73 produced in the lower end of the rod 74 which

extends upwardly and through the top plate 75 and has its upper extremity operatively engaged, as at 76, with the take-up arm 77.

As herein disclosed, the take-up arm 77 is disposed on a predetermined upward curvature and has its lower end pivotally engaged, as at 78, with the block 79 carried by the top plate 75, and the lower end of the take-up arm 77 is provided with the tail-piece 80 with which coacts the spring 81 serving to automatically elevate the outer or free end of said arm.

The outer end of the take-up arm 77 is provided with the eye 82 through which the thread is adapted to be directed and continued to the needle N and for which reason the face plate 83 is provided in its inner surface with the guide channel 84. The face plate 83 serves to incase the slide 53 and to maintain the same in operative assemblage.

The top plate 75 is provided with a spool holder 85 and from which the thread is adapted to coact with the tensioning device T and passes through the well W carried by the plate 16 adjacent the top thereof and at one side of the guideway 54. The thread within the well W is disposed beneath the lower end of the guide member 86 herein disclosed as substantially U-shape in form and having its free extremities pivotally engaged with the walls of the well. The thread is then directed through the opening 87 produced in the upstanding lip 88 positioned intermediate the guideway 54 and the well W and thence through the eye 82 hereinbefore referred to.

The tensioning device T as herein disclosed comprises an elongated plate 89 secured to the upper surface of the top plate 75 with its forward end bifurcated and partially overlying the top of the well W, and the forks of the bifurcated portion are provided with the upstanding ears 90 between which is rotatably supported the grooved pulley 91 over which the thread is directed. The rear portion of the plate 89 is provided with the upstanding transversely spaced ears 92, the space therebetween being intersected by the pin 93 beneath which the thread is also adapted to be directed. Intermediate its length the plate 89 is provided with the upstanding threaded post 94, and encircling said post 94 is the expandable member 95 herein disclosed as a conventional coil spring.

96 denotes a tensioning plate having its forward end provided with the longitudinally directed tongue 97 adapted to extend within the groove 98 of the pulley 91, while the rear end of said plate 96 is provided with a second longitudinally directed tongue 99 adapted to extend between the ears 92. The threaded post 94 is loosely directed through the intermediate portion of the plate 96 and said post 94 has in threaded

engagement therewith above the plate, the nut 100 whereby the tension of the plate 96 or more particularly the forward tongue 97 relative to the thread may be controlled. It is also to be noted that the upper surfaces of the rear ears 92 have their forward portions reduced in order that the tongue 97 may properly coact with said ears.

The plate 16 has coacting therewith the rear plate 101 for incasing the operating member 18 and in order that no obstruction may be offered to the movement of the member 18 by the rod 74, we provide the upper portion of the rear plate 101 in its inner surface with the channel or groove 102 in which the lower end portion of said rod 74 is accommodated. We also provide the rear plate 101 with the opening 103 through which the outer end portion of the shaft 25 extends.

The second bar 22 adjacent its lower end is provided with the inwardly disposed teeth 104 which are adapted to engage the teeth of the disk 105 carried by the shaft 106 disposed through the plate 16, whereby it will be perceived that the shaft 106 will be intermittently rotated in opposite directions.

The forward end of the shaft 106 has affixed thereto a head 107 to which is pivotally engaged the lateral extension 108 of the feed arm 109, and said feed arm 109 is adapted to be moved about its pivot independently of the rocking movement of the head 107 through the medium of the retractile member 110 secured at one end to the lower portion of the feed arm 109 and to the depending portion of a side plate 111 secured to the block 28, said plate 111 having threaded therethrough the member 112 which serves to limit the extent of rocking movement of the feed arm 109 under the influence of the retractile member 110, whereby the extent of feed of the work may be regulated.

The upper end portion of the feed arm 109 is disposed inwardly, as at 113, toward the portion 49 and is provided with the upstanding points or awls 114 to impinge the under surface of the work in order to force the same in the requisite direction. It will be perceived that when the foot lever 12 is depressed, the feed arm 109 will be lowered and retracted relative to the work and that upon the return of the operating member 18 the feed arm 109 will be elevated and caused to rock inwardly to feed the work a predetermined extent. Upon the initial rotation of the head 107 the arm 109 will be caused to move upwardly. The head 107 is adapted to contact with the lateral extension 108 of the arm 109 to cause the upper portion of said arm 109 to rock in a direction toward the portion or work support 49 upon the continued upward rotation of the head 107.

5 In order that the thread may be properly waxed and particularly the under thread, we employ the wax containing box or cup 116 pivotally engaged with the under surface of the table 7 adjacent an end thereof.

10 The box or cup 116 is preferably rectangular in form and is adapted to contain a suitable quantity of thread wax. In the opposite end walls of the box or cup 116 the rod 117 is loosely mounted to rotate. The intermediate portion of this rod 117 is upwardly offset, as at 118, to afford a guide for the thread as it passes through the box. The rod 117 is also provided upon one of its ends and exteriorly of the box 116 with an operating member 119. The opposite side walls of the box 116 are provided at a central point and adjacent their upper edges with the openings 120 through which the thread is adapted to extend.

20 Upon the outer face of one of the side walls of the box or cup 116 and adjacent to the opening 120 therein, is secured the plate 121 which serves as a support for a piece 25 122 of leather or other suitable material and which is maintained in applied position through the medium of the screw 123. The thread as withdrawn from the box or cup 116 passes beneath this piece of leather or the like and the tension or pressure of said piece 122 upon the thread may be regulated as required by the screw 123. It will be apparent that in this manner the surplus wax upon the thread may be removed as the thread is drawn from the wax box or cup 115.

30 124 denotes a tank secured to the under surface of the top plate 75 and adapted to contain a source of fuel supply and leading 40 from said tank 124 is the pipe 125 in communication with the burner 126 rotatably supported below the table 7. It will be perceived that the burner 126 may be conveniently adjusted below the box or cup 116 in order to melt the wax therein or to maintain the same in a molten condition.

45 The burner 126 may also be swung beneath the flue 127 depending from the table 7 and discharging therethrough below the block 28 whereby the thread wound upon the bobbin B within the shuttle S may be maintained at such a temperature to prevent undue hardening of the wax thereon.

55 From the foregoing description, it is thought to be obvious that a sewing machine constructed in accordance with our invention is of an extremely simple and comparatively inexpensive nature and is 60 particularly well adapted for use by reason of the convenience and facility with which it may be assembled, and it will also be obvious that our invention is susceptible of some change and modification without material departure from the principles and

spirit thereof and for this reason we do not wish to be understood as limiting ourselves to the precise arrangement and formation of the several parts herein shown in carrying out our invention in practice, except as 70 hereinafter claimed.

We claim:

1. A sewing machine including in combination, a needle bar mounted for rectilinear movement, a rotary shuttle carrier, an actuating element connected to the needle bar, said element and the shuttle carrier being provided with co-acting means to intermittently rotate the carrier in the movement of the needle bar in each direction. 75

2. A sewing machine including in combination, a rectilinearly movable needle bar, a rotary shuttle carrier, a reciprocatory element connected to the needle bar to actuate the latter, and co-acting means on said element and the shuttle carrier to impart an interrupted rotation to the carrier in the movement of the needle bar in each direction. 80 85

3. A sewing machine including in combination, a reciprocatory needle bar, means for actuating the needle bar including a rectilinearly movable element provided with interrupted rack teeth, and a rotary shuttle carrier having a gear to mesh with the rack teeth, whereby an interrupted rotary movement is imparted to the carrier in the reciprocation of the needle bar. 90 95

4. A sewing machine including in combination, a reciprocatory needle bar and means for actuating the same, a take-up arm pivotally mounted at one end, a rod having a sliding connection at one of its ends to the take-up arm, and operatively connected at its other end to the needle bar actuating means, and means co-acting with the take-up arm to yieldingly urge the same to its normal position. 100 105

5. A sewing machine including in combination, a reciprocatory needle bar and means for actuating the same, a take-up arm pivotally mounted at one of its ends, a rod having a sliding connection at one of its ends to the take-up arm, means connecting the other end of the rod to the needle bar actuating means whereby the rod has a limited movement relative to said actuating means, and a leaf spring co-acting with the pivoted end of the take-up arm to urge the same to 110 its normal position. 115

6. A sewing machine comprising in combination, a reciprocatory needle bar, a reciprocating actuating element operatively connected to the needle bar, a movable spring-held feed bar, an oscillatable member co-acting with the feed bar, and means connected to said member and operatively engaged by the actuating element for the needle bar. 125

7. A sewing machine including in com- 130

bination, a reciprocatory needle bar, a rectilinearly movable, actuating element operatively connected to the needle bar, a pivoted spring-held feed bar, an oscillatable member to co-act with the feed bar and cause an effective movement thereof to feed the material, and means operatively connecting said member to the actuating element for the needle bar.

10 8. A sewing machine including in combination, a reciprocatory needle bar, a rectilinearly movable, actuating element operatively connected to the needle bar, a pivoted feed bar, an oscillatable member co-acting 15 with the feed bar and having a shaft, and means fixed to the said shaft with which said actuating element is adapted to co-act to oscillate the member and cause an effective movement of the feed bar.

20 9. A sewing machine including in combination, a reciprocatory needle bar, a reciprocatory actuating element operatively connected to the needle bar, a feed bar pivotally mounted adjacent one of its ends, a 25 spring connected to the bar and yieldingly holding the same against movement in one direction, a member co-acting with the pivoted end of the feed bar and having a shaft, and a gear element fixed to said shaft, said 30 actuating element for the needle bar having gear teeth to co-act with the gear on the shaft and actuate the member to cause an effective movement of the feed bar.

10. A sewing machine comprising, in combination, a needle bar mounted for reciprocatory movement, an operating member engaged with said needle bar, said operating member comprising two separated bars arranged substantially in parallelism, one of 40 said bars being provided with inwardly directed teeth, means for reciprocating the operating member, a shuttle carrier mounted for rotary movement and including a shaft, and a gear carried by the shaft and adapted 45 to mesh with the teeth of the operating

member for imparting requisite rotation to the carrier.

11. A sewing machine comprising, in combination, a needle bar mounted for reciprocatory movement, an operating member engaged with said needle bar, said operating member comprising two separated bars arranged substantially in parallelism, one of said bars being provided with inwardly directed teeth, means for reciprocating the 55 operating member, a shuttle carrier mounted for rotary movement and including a shaft, and a gear carried by the shaft and adapted to mesh with the teeth of the operating member for imparting requisite rotation to the carrier, the teeth of the carrier being interrupted intermediate their lengths whereby the carrier will remain substantially stationary during a portion of the movement of the operating member.

12. A sewing machine comprising, in combination, a needle bar mounted for reciprocatory movement, an operating member engaged with said needle bar, said operating member comprising two separated bars arranged substantially in parallelism, one of said bars being provided with inwardly directed teeth, means for reciprocating the operating member, a shuttle carrier mounted for rotary movement and including a shaft, 70 a gear carried by the shaft and adapted to mesh with the teeth of the operating member for imparting requisite rotation to the carrier, a feed mechanism, and means coacting with the second bar of the operating member for imparting requisite movement to the feed mechanism.

In testimony whereof we hereunto affix our signatures in the presence of two witnesses.

PETER RASMUSSEN.
MANOEL F. GOULARTE.
